UNITED STATES PATENT OFFICE

THOMAS E. BARNUM, OF WAUWATOSA, WISCONSIN, ASSIGNOR, BY MESNE ASSIGNMENTS, TO CUTLER-HAMMER, INC., OF MILWAUKEE, WISCONSIN, A CORPORATION OF DELAWARE

MOTOR CONTROLLER

Application filed April 11, 1927. Serial No. 182,788.

This invention relates to improvements in motor controllers and more particularly to starters for alternating current motors.

It has heretofore been proposed to provide starters for alternating current motors employing two electromagnetically actuated contactors, one for establishing low voltage starting connections for the motor through the medium of autotransformer windings and the other for connecting the motor directly to the supply circuit for running. In such starters provision is usually made for effecting manual control of the starting contactor and upon closure thereof automatic timing means is brought into operation which acts after a given interval to de-energize the starting switch and energize the running switch.

The present invention has among its objects to improve the construction and operation of starters of the aforesaid character.

Another object is to provide a motor starter of the aforesaid character having improved automatic timing means associated therewith.

Various other objects and advantages of the invention will hereinafter appear.

The accompanying drawings illustrate an embodiment of the invention which will now be described, it being understood that the embodiment illustrated is susceptible of modification without departing from the spirit and scope of the appended claims.

In the drawings:

Figure 1 is a front elevational view of a preferred form of motor starter embodying the invention.

Figs. 2, 3, 4 and 5 are detail side elevational views of certain of the parts illustrated in Fig. 1.

Fig. 6 is a diagrammatic view illustrating the circuit connections of the controller, and,

Fig. 7 is an across-the-line diagram of the control circuits illustrated in Fig. 6, the auxiliary contacts being shown in the position they occupy during starting.

Referring to Fig. 1, the same illustrates a starter for alternating current motors including electromagnetically operated contactors 1 and 2 mounted upon an insulating

panel 3. As hereinafter set forth contactor 1 provides for establishment of starting connections for the motor through the medium of auto-transformer windings, while contactor 2 provides for connection of the motor directly to the supply circuit for running. Contactor 1 is manually controlled, and as hereinafter set forth upon closure thereof an automatic timing device is brought into action which causes de-energization of said starting contactor and energization of the running contactor after the lapse of a predetermined interval.

Starting contactor 1 and running contactor 2 are each provided with an operating magnet of the character shown in Fig. 4 comprising an operating winding 4 provided with a pivoted armature 5 supported between bearing members 6. In the following description the operating winding of starting contactor 1 is designated by reference character 4^a and the operating winding of running contactor 2 by reference character 4^b. The armature 5 of contactor 1 is operatively connected to a rotatable shaft 7 and said shaft carries insulated contact fingers 8 to 12, inclusive, each of which has a cooperating stationary contact. Said contact fingers are normally in open position but upon energization of the associated magnet, shaft 7 is rotated on its axis to move said contact fingers into engagement with their cooperating stationary contacts. As herein-after set forth contact fingers 9, 10 and 11 control the line connections for the motor during starting and to prevent excessive arcing between these fingers and their cooperating stationary contacts upon interruption of starting connections each is provided with a magnetic blowout device 13. The armature 5 of running contactor 2 is operatively connected to a rotatable shaft 17 upon which are mounted insulated contact fingers 18, 19 and 20, each of which has a cooperating stationary contact. The running contactor 2 is biased to open position and upon energization of its operating magnet the shaft 17 is rotated to effect closure of contact fingers 18, 19 and 20. Each of the contact fingers 18, 19 and 20 has a blowout device 21 associated with it.

therewith, said devices being similar to the blowout devices 13.

The starting and running contactors are provided with mechanical interlocking means comprising levers 25 and 26 fixed to shafts 7 and 17, respectively. As best shown in Fig. 2 lever 25 is arranged so that the free end thereof projects into the path of lever 26 to prevent closure of the running contactor 2 while starting contactor 1 is in closed position. However, for purposes hereinafter set forth said interlocking means permits partial movement of the running contactor 2 towards closed position while the starting contactor 1 is in closed position.

The timing device hereinbefore mentioned, is best illustrated in Fig. 3 and includes a contact arm 30 having a dash pot 31 associated therewith, the latter being provided with a cylinder 32 and a piston 33 and being designed to provide retarded upward movement of said piston and substantially free downward movement thereof. The cylinder 32 is fixed to insulating panel 3 and the same is provided with upstanding projections 34 carrying a pin 35 upon which the contact arm 30 is pivotally mounted. The piston 33 is operatively connected to the contact arm 30 by a rod 36 having a hook portion 37 on the upper end thereof for engaging a pin 38 fixed to said contact arm. Contact arm 30 carries a bridging contact 39 on the free end thereof and the same is biased by a spring 40 to move said bridging contact into engagement with a pair of stationary contacts fixed to panel 3, one of which is illustrated by reference character 41 in Fig. 3. Spring 40 has one end connected to the contact arm 30 while the opposite end thereof is adjustably secured to a projection 42 on the lever 25. Lever 25 is also provided with a projection 43 having an adjustable stop 44 thereon for engaging a projection 45 on contact arm 30. The stop 44 normally holds the contact arm 30 in the position shown in Fig. 3, but upon closure of starting contactor 1 said arm is moved by spring 40 against the action of the dash pot 32 to bring the bridging contact 39 into engagement with contacts 41. Upon opening of starting contactor 1 the stop 44 engages the projection 45 on contact arm 30 to move the latter to open position and the dash pot piston 33 quickly returns to normal position under the action of gravity.

As best shown in Fig. 4, the operating armatures for the starting and running contactors are each provided with downwardly extending tail pieces 46 and the tail piece associated with the former contactor carries pins 48 and 49 on opposite sides thereof while the tail piece associated with the latter contactor carries pins 50 and 51 on opposite sides thereof. The pin 49 cooper-

ates with a pair of stationary contacts 52 of the construction shown in Fig. 5, while the pin 50 cooperates with a pair of similar stationary contacts 53. As shown in Fig. 5 each of the stationary contacts 52 and 53 is yieldingly mounted upon a supporting bracket 54 which is fixed to insulating panel 3 and the contacts 52 are arranged to be bridged by pin 49 upon closure of starting contactor 1 while contacts 53 are arranged to be bridged by the pin 50 upon closure of the running contactor 2. Pin 48 has a contact element 55 associated therewith which cooperates with a stationary contact 56 while pin 51 has contact elements 57 and 58 associated therewith which cooperate with stationary contacts 59 and 60, respectively. The contact elements 55, 57 and 58 are of similar construction and as best shown in Fig. 4 each of the same is provided with openings for receiving a pair of supporting pins 61 and 62 which are fixed to panel 3. Each of the supporting pins 61 carries a cotter pin 63 adjacent its outer end which forms a pivot for its associated contact element, while each of the supporting pins 62 carries a spring 64 for biasing its associated contact element in a direction away from panel 3. The stationary contacts associated with contact elements 55 and 57 are of similar construction and as shown in Fig. 4 each of the same is fixed to panel 3 and is provided with a downwardly projecting portion to be engaged by its associated contact element upon outward movement thereof under the action of the spring 64. For purposes hereinafter set forth contact elements 55 and 57 are normally held in open position by pins 48 and 51, and the arrangement is such that the former contact element engages its contact 56 upon initial closing movement of starting contactor 1, while the latter element engages its contact 59 upon initial closing movement of running contactor 2. The stationary contact 60 as shown in Fig. 4 is shorter than the stationary contact 59 and the arrangement is such that the same is engaged by contact element 58 when running contactor 2 is in open position. However, upon initial closing movement of the running contactor 2 the pin 51 permits contact member 58 to move outwardly under the action of its spring 63 for disengagement thereof with contact 60.

The operation of the aforescribed auto-transformer starter and also the circuit connections therefor will now be more fully described in connection with Fig. 6 and Fig. 7. As shown in Fig. 6 the starter provides for selective establishment of starting and running connections for an alternating current motor M from a 3 phase supply circuit indicated by lines L¹, L² and L³. Lines L¹, L² and L³ are permanently connected to the stationary contacts associated with contact fin-

gers 9, 10 and 11 and also to the stationary contacts associated with contact fingers 18, 19 and 20. The stationary contacts of contact fingers 8 and 12 are permanently connected to low voltage taps on auto-transformer windings C^1 , C^2 respectively, and compensator winding C^1 is permanently connected between contact fingers 9 and 10 while the compensator winding C^2 is permanently connected between contact fingers 10 and 11. Terminal T^1 of the motor M is connected to contact fingers 8 and 18; terminal T^2 is permanently connected to contact fingers 10 and 19, while terminal T^3 is permanently connected to contact fingers 12 and 20. With the connections above described it is apparent that upon closure of starting contactor 1 the motor is supplied with low voltage starting current from lines L^1 , L^2 , L^3 through the medium of auto-transformer windings C^1 and C^2 while closure of running contactor 2 connects the motor directly to said lines for running.

Starting contactor 1 is controlled by a normally open start push button 65 and a normally closed stop push button 66 and upon depression of the former button an energizing circuit for the operating winding 4^a of said contactor is established extending from line L^1 through push buttons 66 and 65, by conductor 70 to and through the operating winding 4^a of said starting contactor and thence by conductor 71 to line L^2 . As before stated, upon closure of starting contactor 1 the member 49 bridges stationary contacts 52 and a maintaining circuit for said starting contactor is then established extending from line L^1 through push button 66, by conductors 72 and 73, to and through the normally closed contact element 58 associated with the running switch 2, by conductor 74 through the contacts 52 and thence through the operating winding 4^a of the starting contactor to line L^2 .

Upon closure of starting contactor 1 the timing device is brought into operation and after a given interval the bridging contact 39 thereof engages the cooperating stationary contacts 41. Upon engagement of contacts 41 by contact 39 an energizing circuit for the operating winding 4^b of the running contactor 2 is established extending from line L^1 through push button 66, by conductor 75, through contacts 41, by conductor 76 to and through the operating winding of the running contactor and thence by conductor 71 to line L^2 . Energization of the operating winding 4^b of the running contactor tends to effect closure thereof, but as before stated, when the starting contactor 1 is in closed position the lever 25 associated therewith cooperates with the lever 26 associated with the running contactor 2 to permit only partial closing movement of the latter contactor. Such partial closing movement of the

contactor 2 effects opening of the contact element 58 and closure of contact element 57. Opening of contact element 58 interrupts the aforescribed maintaining circuit for the operating winding of starting contactor 1 and said contactor and the timing device associated therewith then return to normal position. During return of the starting contactor 1 to normal position, the operating winding 4^b of running contactor 2 is maintained energized by a circuit extending from line L^1 through the normally closed push button 66, by conductors 72 and 78, through the contact element 55, by conductor 79, through contact element 57, by conductor 76, through the operating winding 4^b , thence by conductor 71 to line L^2 . This maintaining circuit is interrupted by opening of contact element 55 upon return of the starting contactor 1 to off position, but in the meantime the running contactor 2 has moved into closed position and is maintained by a circuit extending from line L^1 through push button 66, by conductor 72, through the contacts 53, by conductor 76, through the operating winding 4^b of the running contactor 2 to line L^2 . This maintaining circuit may be interrupted by depression of push button 66 to provide for return of the running contactor 2 to off position. Upon opening of the running contactor 2 there is a tendency for the same to rebound. However, it should be noted that since the contacts 53 are bridged only upon full movement of the running contactor 2 into closed position it is impossible for said contactor to rebound sufficiently to reestablish the aforescribed maintaining circuit therefor.

What I claim as new and desire to secure by Letters Patent is:

1. A controller for electric motors comprising two electromagnetically operated switches, one for starting and one for running, control means for said running switch including a time element switch member to be set in operation upon response of said starting switch, and means operating upon response of said running switch for deenergizing said starting switch and for maintaining said running switch energized independently of said time element switch member.

2. A controller for electric motors comprising two normally open electromagnetically operated switches, one for starting and one for running, control means for said running switch including a spring actuated time element switch member to be set in operation upon response of said starting switch, means associated with said running switch and acting upon initial closing movement thereof to deenergize said starting switch, and means associated with said running switch for maintaining the same energized

independently of said time element switch member.

3. A controller for electric motors, comprising two electromagnetically operated switches, one for starting and one for running, mechanical interlocking means between said switches permitting a limited movement of said running switch towards closed position upon closure of said starting switch, means for controlling the energizing circuit of said running switch comprising a spring actuated time element switch member retarded in its action and set in operation by closure of said starting switch, and means associated with said running switch and acting during said limited closing movement thereof to deenergize said starting switch.

4. A controller for electric motors, comprising two electromagnetically operated switches, one for starting and one for running, a time element device arranged to act upon closure of said starting switch to establish an energizing circuit for said running switch and means acting upon a given closing movement of said running switch to deenergize said starting switch and to maintain said running switch energized independently of said time element device.

5. A controller for electric motors comprising two electromagnetically operated switches, one for starting and for running, a time element device arranged to act upon closure of said starting switch to establish an energizing circuit for said running switch, a mechanical interlock between said switches permitting a limited closing movement of said running switch upon closure of said starting switch and means adapted to act during said limited closing movement of said running switch to deenergize said starting switch and to maintain said running switch energized independently of said timing device during return of said starting switch to open position.

6. A controller for electric motors comprising two electromagnetically operated switches, one for starting and one for running, a mechanical interlock between said switches permitting a limited closing movement of said running switch upon closure of said starting switch, a time element device arranged to act upon closure of said starting switch to establish an energizing circuit for said running switch, means adapted to act during closing movement of said running switch to deenergize said starting switch and to maintain said running switch energized independently of said timing device pending return of said starting switch to open position and means adapted to act only upon closure of said running switch to maintain the same energized independently of said timing device.

7. In a controller for electric motors, in combination, two electromagnetically oper-

ated switches, one responsive to establish starting connections and the other responsive to establish running connections, a manually operated control switch for said starting switch, means for establishing a maintaining circuit for said starting switch upon closure thereof comprising normally closed contacts associated with said running switch and normally open contacts associated with said starting switch, a time element device arranged to act upon closure of said starting switch to establish an energizing circuit for said running switch, and contacts associated with said running switch and acting upon closure thereof to shunt said time element device.

In witness whereof, I have hereunto subscribed my name.

THOMAS E. BARNUM.
